UNITED STATES PATENT OFFICE.

RODOLPH STUART O'NEIL, OF LONDON, ENGLAND.

ELECTRICAL INDICATING DEVICE.

Application filed March 1, 1920. Serial No. 362,417.

To all whom it may concern:

Be it known that I, RODOLPH STUART O'NEIL, a subject of the King of Great Britain, and a resident of London, England, 5 have invented certain new and useful Improvements in Electrical Indicating Devices, of which the following is a specification.

This invention relates to electrical indicating devices, and has particular reference 10 to indicators for use in apparatus for signalling the position of a ship's helm. Although regarded as useful in other signalling systems, it is particularly advantageous in systems such as that disclosed in the specification of my application for Letters Patent in the United States for Improvement in electrical indicating devices, filed Feb. 11, 1920, Serial Number 357,890, 15 Patent No. 1,877,427, dated May 10, 1921. The invention consists of an indicator comprising a casing having a single display opening and means for interposing between a light and this display opening a pre-selected disc or slide having upon it the indication it is desired to expose. The invention is illustrated diagrammatically in the accompanying drawings, in its particular application to a helm signalling system.

30 In these drawings Fig. 1 is a transverse section and Fig. 2 a front elevation of an indicator constructed in accordance with my invention.

Fig. 3 is a diagram showing the rudder 35 post, the drum, the contacts and the electrical circuits.

Referring to these drawings the numerals 1, 2 and 3 designate lamps each of a different colour, for instance 1 being a white lamp, 40 2 a green lamp, and 3 a red lamp, each of which is automatically brought into circuit in pre-selected manner as, for instance, in the manner described in the specification of my application before alluded to.

45 Surrounding the display opening 4 a number of electromagnetic devices are disposed, these devices each consisting of an electro-magnet 5 having a pivoted armature 6 which is connected by a pivoted link 7 to an arm 8 rigidly attached to a translucent pivoted disc 9 upon which the indication it is desired to convey is applied. Thus when circuit to the magnet 5 is completed, the armature 6 is attracted and the disc 9 50 will be moved so as to become interposed be-

tween the lamps 1, 2 and 3 and the display opening 4. In Fig. 2 the positioning is illustrated, but for convenience the discs 9 have been shown in front elevation, whereas in fact they would be seen in edge view as 60 will be readily understood.

In the particular application of my invention illustrated—that of the indicator of a helm signalling device—the operation is as follows, and will be clearly understood upon 65 reference to Figure 3, described later. With the helm in central position the white light 1 will be illuminated and when the helm moves to "port" or "starboard," the appropriate red or green light as the case may be 70 will appear. When the helm is 5 degrees on either side, circuit will be completed to the electro-magnetic device controlling a disc having the number 5 applied to it. When the helm is 10 degrees over on either 75 side, the circuit to the magnetic device controlling the disc having the indication 10 will be completed and therefore at various positions of the rudder the corresponding disc comes into display position in accordance with the rudder movement, and a clear 80 indication of the rudder position is given by the combination of the number displayed and the colour.

Referring to Fig. 3 of the drawings, the 85 numeral 11 designates the rudder post which is connected to a contact drum 12. The contact drum 12 has its contacts arranged to correspond with certain positions of the rudder. For the moment it is only necessary to consider three positions, corresponding to the central position of the rudder and positions both to "port" and "starboard." The contact drum 12 moves with the rudder post 11, and I provide a pair of contacts 13 and 14, one corresponding to the "port" and the other to "starboard." These contacts 13 and 14 are arranged on the drum 90 on either side of the central position and one or other of them serves, by cooperation 95 with a stationary contact 13^b or 14^b to complete the circuit of an electric lamp or indicator 1 or 2 respectively each of a particular color. With the rudder in precisely the 100 central position, neither of the drum contacts 13 and 14 will engage their respective cooperating stationary contacts 13^b or 14^b and no fresh indication will be given, but 105 any deviation of the rudder from the central position will cause contact to be made 110

between one or the other of the drum contacts 13 and 14 and in one or other of the cooperating contacts 13^b or 14^b and one or other of the lamps 1 or 2 will be illuminated 5 or one or other of two indications made. The lamp or indicator signal associated with the "port" contact 13 may be one color, and that associated with the "starboard" contact 14 another, so that immediately after either of 10 the lamps becomes illuminated the helmsman or other person provided with indication lamps will know that the rudder has moved from the central position and the color of the light or indicator exhibited will 15 inform him as to the direction of the movement.

Various positions of the rudder are indicated by reason of drum contacts 17 connected together in pairs cooperating with 20 stationary contacts 18, through which circuits to indicator coils (or lamps) 5 are established. Thus the various actual positions mentioned of the rudder will be signaled.

It has been noted that the central position of the rudder may be indicated by a 25 white light or indicator and in the diagram this lamp or indicator is designated 3. Current passes to the drum from the positive line to the stationary contacts 16 with which 30 the drum contact 16^b cooperates. In the central position of the rudder a stationary contact 16^c coincides with a drum contact and when the rudder moves, say five degrees, in either direction, the drum contact 35 becomes separated from the stationary con-

tact and the white light goes out, a colored light being substituted.

Although I have described my invention in its application to helm signalling, it will be understood that it may be applied to 40 other indicators.

What I claim and desire to secure by Letters Patent is:—

An indicator for indicating the position of a ship's helm, comprising a casing having 45 a display opening, illuminating devices behind said opening and each of a different color, a plurality of pivoted and transparent discs spaced around said opening and having indicia, a corresponding number of electro-magnet devices operatively connected to said discs, and switching means operatively connected to the ship's rudder and cooperating with the illuminating and electromagnet devices whereby the movement of said helm 55 to one side of the neutral position causes one of said illuminating devices to be energized and movement of the helm to the other side causes another of said illuminating devices of different color to be energized, said 60 movement also causing one or other of the magnetic devices to be energized so as to interpose the corresponding disc between the illuminating device and the display opening, said disc indicating the approximate number of degrees of movement of the helm on either side of the neutral position. 65

In witness whereof I affix my signature.

RODOLPH STUART O'NEIL.
